3 Claims

2

pose of allowing the braces 27 to extend outwardly of the collar. Likewise a plurality of slots 30 are provided near the upper end of the outer tube for purpose of allowing the lower end of each of the arms to extend outwardly therefrom. The upper terminal end of each of the arms is pointed as is shown at 31.

In operative use, the outer sleeve or out tube 19 is manually drawn downwardly to cause the arms 24 to be withdrawn inwardly into the position as is shown in FIGURE 4 of the drawing, at which time a spool or ball of crochet thread 14 may be readily inserted thereupon as is shown in FIGURE 1 of the drawing. Upon release of the outer tube, the compression coil spring 22 will normally urge the outer tube upwardly to cause the arms 24 to spread radially outwardly and to bind upon the spool of thread or yarn. Thus the spool is secured upon the holder and the spool is rotatable in view of the bearing 16 at the lower end of the stanchion 17. Thus as the spool rotates, the thread may be pulled freely therefrom without the necessity of stopping.

While various changes may be made in the detailed construction it is understood that such changes will be within the spirit and scope of the present invention as is defined by the appended claims.

I claim:

1. In a holder for spools of thread, the combination of a base, an upstanding post and an arm assembly at the upper end of said post, said arm assembly having self contained means for grasping a spool of thread and holding the same upon the end of said post so to allow rotation of said spool of thread while being retained thereupon as thread is freely pulled therefrom, said holder including a recess within the upper side of said base, a bearing contained within said base, said post comprising a central stanchion, the lower end of said stanchion being fitted within said bearing, the upper end of said stanchion having a collar forming a part of said arm assembly and said post further including an inner tube and an outer tube around the said inner tube, said inner tube having a shoulder at the lower end of a compression coil spring and supporting the same thereupon, said outer tube having a shoulder at its upper end and having the upper end of said compression coil spring bearing thereagainst, for normally urging said outer sleeve upwardly and thus normally urging said arm assembly into a spinning position for normally securing said spool of thread thereto.

2. The combination as set forth in claim 1 wherein said arm assembly comprises a plurality of four arms, the lower end of each of said arms being pivotally secured to a wire ring carried at the upper end of said wire tube, an intermediate portion of said arms being secured pivotally free to a brace, one end of said brace being secured pivotally free around a wire ring carried within said collar, and the outer upper end of each of said arms being pointed.

3. The combination as set forth in claim 2 wherein a slot is provided in said collar to allow the end of each brace to be fitted upon said wiring contained in said collar, and the lower end of each of said arms extending through a slot near the upper end of said outer tube to allow the lower end of said arm to be pivoted upon said wiring carried by said upper end of said tube.

The present invention includes an arm assembly 23 comprised of four arms 24, each of which is pivoted at its lower end about a wire ring 25 carried by the outer tube, each arm at its mid portion being connected by a pin 26 to a brace 27 which at its opposite end is secured pivotally free to a wire ring 28 carried within the collar 18. A plurality of slots 29 are provided in the collar for pur-
